structions Mécaniques, a corporation of France

Application July 9, 1949, Serial No. 103,904
In France July 21, 1948

3 Claims. (Cl. 332—11)

1

This invention relates to systems for transmitting complex intelligence waves in which the instantaneous amplitudes of said waves are analyzed at recurrent time intervals and the amplitude samples thus obtained are translated into coded signals consisting of groups of an integer number n of pulses, each pulse of which can assume one or the other of two values or possible signalling conditions. It relates more particularly to coder and decoder devices comprising essentially electronic tubes containing means for generating an electron beam, means for deflecting said electron beam, an electron collecting anode and a mask or apertured electrode with cut out parts inserted on the path of the beam.

In the same way as other and previously known coder systems, the performance of the hereunder described coder device is essentially based on the fact that after the above mentioned sampling and previous to its being translated into code signals, the complex intelligence wave to be transmitted is first transformed into an electric voltage, hereinafter called the "modified signal voltage," having a square wave-shape whose peaks have amplitudes related to the sampled amplitudes, being, for instance, proportional to the latter. It is further known that, in practice an exact proportionality is unnecessary. If the sample amplitudes vary between extreme values respectively proportional to integer numbers 1 and 2^n , it is generally deemed sufficient to give the modified signal voltage one of a series of 2^n distinct values and to substitute for the exact proportional value corresponding to the sampled amplitude the nearest approximation to it, by excess or defect, in the series just mentioned. Devices for obtaining such a modified signal voltage from an intelligence wave are well known in the art.

Transmitting systems are known, essentially comprising coding devices made up of electronic tubes wherein the electronic beam is deflected in a first direction, by an amount depending on the amplitude of each sample, then deflected in a second direction to scan the mask and generate in the anode circuit groups of pulses, each one of which corresponds to the passing of the beam through one of the cut-out portions of the mask. In such tubes, the mask should comprise as many groups of solid or cut-out portions, usually in a two dimensional array as there are distinct sampled amplitudes. The two-dimensional scanning of a predetermined group by the beam raises difficulties. According to one of the main characteristics of the invention, the transmitting device comprises essentially a tube of simpler

2

construction wherein the combinations of pulse groups are generated by displacement and scanning in one direction only, the mask comprising a single row of cut out portions.

5 The invention is based on the fact that it is possible to classify all the 2^n possible groups of n pulses, each of which may assume either one of two values and representing the 2^n amplitudes distinguished during the sampling of a complex wave into such an order that the $(n-1)$ last pulses of a group have individually the same values as the $(n-1)$ first pulses of the following group.

15 For instance, in the case where $n=4$, according to a well known convention, if the two possible values of each pulse are represented by the figures 0 and 1, the 16 possible groups may be arranged as follows:

20 1111 1110 1101 1011 0110 1100 1001 0010
0101 1010 0100 1000 0000 0001 0011 0111

By writing the same combinations successively and having them overlap so as to have the three last figures of one combination identical with the 25 three first figures of the following combination, one obtains:

1 1 1 1 0 1 1 0 0 1 0 1 0 0 0 0 1 1 1

According to one feature of the invention, at 30 the sending end of a transmission system the coder device comprises essentially a tube containing means for generating an electronic beam, means for deflecting said beam in one direction, an electron collecting anode and a mask interposed on the beam trajectory and comprising a row of solid or cut out elements, said cut out portions being arranged in such a manner that when the mask is scanned by the beam, the 2^n possible combinations of solid or cut out elements 35 are met only once, taking the $(n-1)$ last elements of each combination as the $(n-1)$ first elements of the following combination.

For instance, in the case where $n=4$, already 40 considered above, the solid and cut-out elements of the mask may correspond respectively to the figures 0 and 1 of the sequence of 16 binary figures written above.

The transmitting devices according to the 45 invention comprise essentially a tube in accordance with the above description, means operative during the duration of each sampling to deflect the beam in the tube by an amount determined by the amplitude of the modified signal voltage, means for superimposing on the preceding deflection the scanning, in recurrence with each

modified signal voltage of a number of solid or cut out elements of the mask equal to the number of pulses in the coded groups, and means for collecting the pulses generated in the circuit of the anode of the tube by the passing of the beam through the cut out portions of the mask.

The invention will now be more particularly described with reference to the accompanying drawings illustrating the application of the method according to the invention to a multiple telephone transmission device. In the drawings,

Figure 1 illustrates, schematically, a coder electron tube which constitutes the essential element of the device;

Figure 2 illustrates, in front view and on a larger scale, one of the electrodes of the above tube;

Figure 3 illustrates a block diagram of the main elements of a two channel transmitting device constructed in accordance with the invention;

Figure 4 is a diagram representing the wave shape of the voltages applied to certain electrodes of the coder tube of a transmission channel as well as the shape of the code signals generated by this tube.

In the example shown, the amplitude of the signal in each channel is sampled with a recurrent frequency F and the amplitude value is finally transmitted in the form of a conventional signal constituted by n pulses. The sampling times in the various channels are offset with respect to one another so as to ensure, in each cycle of frequency F the successive transmission of a code signal group for each one of the N channels associated in the multiple transmission. The possible range of variation of the signal amplitude is divided into 2^n elementary intervals provided with a rank number.

In order to simplify the description now given of a practical application of the invention, it will be described as applied to a transmission assembly having two channels (i. e. $N=2$) and making use of code signal group constituted by four pulses, (i. e. $n=4$).

The coder tube 1, illustrated in Figure 1, which is an electron tube according to the invention, comprises an electron emitting cathode 2, an electrode 3 controlling the intensity of the electron beam and operable to suppress the same, a focussing electrode 4, vertical deflection plates 5, an electrode 6 consisting of a mask provided with windows and a collecting anode 7.

The mask electrode 6, disposed along the deflection part of the electron beam shown in front elevation in Figure 2 comprises a plurality of narrow horizontal windows 8, whose distribution along the major axis of the electrode corresponds to that of the figures in the basic sequence, hereinbefore referred to, there being one window corresponding to each figure 1 of said sequence, and the various solid parts or windows individually representing figures in said sequence having equal or nearly lengths along said major axis. The corresponding rank for the 16 figures of the sequence has been indicated opposite the corresponding intervals on the screen 6.

The various electrodes of the tube 1 are energized in accordance with the conventional technique, by voltages ensuring their normal operation. The control electrode and the deflection plates are subjected respectively, to voltages which, (a) start the beam only at certain instants and (b), vary the point of impact of the

beam on the mask electrode as will be hereinafter explained.

In the block diagram illustrated in Figure 3, 31 represents a basic generator supplying the frequency F . 32 and 32' represent the two coder tubes of the two associated channels. The code signals generated, alternately, by these tubes are applied by line 33 to the transmission circuit. 34 and 34' are two square wave voltage generators each controlled by the basic generator 31 and each actuating the beam intensity control electrode of its associated tube so as to cause an alternate starting of the beams of the two tubes; 35 and 35' are two saw tooth voltage generators controlled by the basic generator 31 and actuating, in alternation, the deflection plates of the two tubes. 36 and 36' are two square wave voltage generators also controlled by generator 31, actuating, in alternation, the deflection plates of the two tubes. These square wave voltages are respectively amplitude modulated from the signal voltages in each channel, which are supplied by lines 37, 37', and constitute what has been hereabove called the modified signal voltage to the instantaneous amplitude of the signal at one sampling instant.

The operation of the above elements will be better understood by referring to Figure 4, where the times and signal amplitudes have been represented on two axes of co-ordinates. The figure refers to the first one of the two associated channels.

The curve 41 shows, on an arbitrary scale, the amplitude of the signal of the first channel as a function of time. The time interval 43-44 is allotted to the transmission of a signal from the first channel, 44-45 to a signal from the second channel, 45-46, again to a signal from the first channel and so on. The time interval 43-45 is the reciprocal of the sampling frequency F .

Each interval such as 43-44 is divided into four elementary intervals, each of them allotted to the sending of a pulse of the four element code signal group.

The saw tooth curve 47 shows the voltage provided by the generator 35 and applied to the deflection plates of the electron tube.

As a square wave voltage, in phase with the said saw tooth voltage, is applied by the generator 34 to the intensity control electrode of the electron tube, the beam is on only during the time intervals 43-44, 45-46, etc.

The straight line segments 49 represent the resultant voltage applied to the deflection plates at the times when the beam is on, which voltage is the sum of the saw tooth voltage 47 and the amplitude modulated square wave voltage or modified signal voltage 48. The height (that is to say the position intermediate the ends of the screen electrode), of the impact point of the beam on the mask electrode is proportional to this voltage. The correspondence between the window locations on the mask electrode and the voltages applied to the deflection electrodes has been shown on a vertical axis at the right hand side of the figure.

It will be seen that the amplitude of the square wave voltage 48 has been adjusted in such a manner that the beam impact sweeps 16 intervals of the screen when the signal voltage passes from its minimum to its maximum value and that the amplitude of the saw tooth voltage 47 has been adjusted so as to cause a deflection of four intervals.

At the instant 43, at which the amplitude of 41 has been sampled, the deflection voltage is raised

to 52 and then comes back, linearly, to the level 51. The slope of the saw tooth wave is adjusted in such a manner that this part of it is gone through during the time interval 43-44. During this time, the beam sweeps through four intervals of the mask and the tube passes a short pulse every time the beam goes through a window. The pulses thus generated constitute the code group characterizing the amplitude of 41. This group, comprising in the example shown one pulse during the second and third elementary intervals, is shown at 53.

A similar process is effected during the time interval 45-46. The code group generated comprises only one pulse during this last interval.

It will be noted that the pulses thus generated can be shifted relatively to time due to the fact that the amplitude of the signal does not generally correspond to a whole number of elementary amplitude intervals by a duration smaller than that of the elementary interval. The signal combination is, however, formed without any uncertainty, provided the mask electrode windows are narrow enough.

The code signals of the second channel are generated in the same manner, the only difference being that the signals must be generated in alternance with those of the first channel. The operating time shift of the elements in the two channels is obtained easily since all the elements of the signal generating circuits are controlled by the same basic generator.

It is evident that the invention applies to a transmission system having any number of channels, the electron tubes being merely actuated alternately as a polyphase system.

The present invention also applies to systems of secret transmission in which the signals must be impossible to decipher without the knowledge of a secret code.

In accordance with the method of the invention described above, the correspondence between the amplitude value of a signal to be transmitted and the corresponding code signals is effected through a sequence of 2^n binary digits, which ensures a relative secret. The secret nature of this transmission may be made practically absolute by varying, in time, the rank from which are counted, in the basic sequence, the combinations of n digits and consequently the correspondence between the amplitude values and the code signals.

These variations can be effected in a practically instantaneous manner and synchronously at the two ends of the communication link. The instants and amplitudes of these variations may be the objects of a secret code known only to the authorities responsible for the transmission.

The embodiment of the invention described above by way of example, concerns a multiple telephone transmission system. It will be realized that the invention is also applicable to any telecommunication system, simple or multiple, wherein a succession of messages must be transmitted in the shape of code signals.

What we claim is:

1. An electron tube for use in a coder for translating an intelligence wave represented by a variable electric voltage occurring at recurring time intervals into groups of code signals, each group comprising an integer number n of pulses, each pulse being of one or the other of two possible signalling conditions; said electron tube comprising a cathode emitting electrons, an electron gun for the production of an electronic

beam, a control electrode for establishing or interrupting said beam, deflecting electrodes for deflecting said beam in a given direction under the action of an external voltage, an apertured electrode disposed in the path of said beam and having a single row of solid and cut out portions extending along said given direction and numbering $2^n + (n-1)$, said solid and cut out portions being arranged in such an order that each group of n consecutive solid and cut out portions is different from any other such group, and an anode for collecting the electrons of said beam which pass through the cut out portions of said apertured electrode.

2. In a communication system in which the amplitude of an intelligence wave is sampled at recurring time intervals and each sampled amplitude is thereafter represented by a group of a fixed integer number n of permutation code signals which are of one or the other of two different possible signalling conditions; an electronic device for converting said intelligence wave into code signals, comprising an electronic tube including a cathode emitting electrons, an electron gun for the production of an electronic beam, a control electrode for establishing or interrupting said beam, deflecting electrodes for deflecting said beam in a given direction under the action of an external voltage, an apertured electrode disposed in the path of said beam and having a single row of solid and cut out portions extending along said given direction and numbering $2^n + (n-1)$, said solid and cut out portions being arranged in such an order that each group of n consecutive solid and cut out portions is different from any other group of n consecutive portions, and an anode for collecting the electrons of said beam which pass through the cut out portions of said apertured electrode, an external circuit connected to said anode, means effective during each sampling of the intelligence wave to be converted into code signals for applying to the said deflecting electrodes a voltage approximately proportional to the sample amplitude of said intelligence wave thereby directing said electron beam at a related predetermined part of said apertured electrode, means for applying to said control electrode a controlling voltage so as to establish said electron beam only during predetermined recurring time intervals, means for applying to said deflecting electrodes and during said recurring time intervals a sweeping voltage so as to cause said electron beam to sweep said predetermined part of said mask apertured electrode along said given direction and over a distance encompassing n consecutive portions of said apertured electrode, thereby causing a sequence of pulses to be produced in said external circuit, and means for impressing said pulses upon a working circuit.

3. In a communication system using coded signals, and including at least one communication channel in each one of which the amplitude of an intelligence wave is sampled at recurrent time intervals and wherein each sampled amplitude is thereafter represented by a group of n permutatable pulses, each pulse being of one or the other of two possible signalling conditions; a transmitting device comprising a main generator of electric oscillations having a basic frequency corresponding to the recurrent time intervals for sampling of the amplitude of said intelligence wave, at least one electronic tube, each said electronic tube including a cathode emitting electrons, an electron gun for the production of an

electronic beam, a control electrode for establishing or interrupting said beam, deflecting electrodes for deflecting said beam in a given direction under the action of an external voltage, an apertured electrode disposed in the path of said beam and having a single row of solid and cut out portions extending along said given direction and numbering $2^n + (n-1)$, said solid and cut out portions being arranged in such an order that each group of n consecutive solid and cut out portions is different from any other group of n consecutive solid and cut out portions, and an anode for collecting the electrons of said beam which pass through said cut out portions of the apertured electrode, a generator of square wave-shaped electric voltage having its frequency and phase controlled by the said main generator, means for controlling the amplitude of said square wave-shaped voltage proportionally to the sample amplitude of the intelligence wave to be transmitted, means for applying said square wave-shaped voltage to the deflecting electrodes of each said electronic tube thereby directing said beam at a predetermined related part of said apertured electrode, a generator of saw-tooth electric voltage of a predetermined amplitude having its frequency and phase controlled by the said main generator, means for applying said saw-tooth voltage to the deflecting electrodes of each said electronic tube simultaneously with said square wave-shaped voltage to cause said

beam to sweep said related part of the apertured electrode of a distance encompassing n consecutive portions of said apertured electrode, an external circuit collecting the current from the anode of each said tube, and means for impressing said current upon a working circuit.
